United States Patent Office

Des. 209,258
Patented Nov. 14, 1967

209,258

LOG GRATE

Carroll E. McDonald, P.O. Box 1229,
Lakeview, Oreg. 97630

Filed Jan. 11, 1967, Ser. No. 5,384

Term of patent 14 years

(Cl. D81—18)

FIG. 1 is a perspective view of a log grate in accordance with my new design;

FIG. 2 is a front elevational view thereof; and

FIG. 3 is a side elevational view thereof.

I claim:

The ornamental design for a log grate, as shown.
